(57) **CLAIM**

The ornamental design for an articulated frame for folding awnings, as shown and described.

DESCRIPTION

FIG. 1 is a front perspective view of an articulated frame for folding awnings;

FIG. 2 is an enlarged fragmented front perspective view in folded position;

FIG. 3 is an enlarged fragmented front elevation view in folded position;

FIG. 4 is an enlarged top plan fragmented view in folded position;

FIG. 5 is an enlarged fragmented rear elevation view in extended position;

FIG. 6 is an enlarged fragmented bottom plan view in extended position; and,

FIG. 7 is a rear perspective view in extended position.

The arms of the claimed design are broken indicating indeterminate length.
